UNITED STATES PATENT OFFICE.

CHARLES CARROLL GILMAN, OF ELDORA, IOWA.

UNDERGROUND RAILWAY-CONDUIT.

SPECIFICATION forming part of Letters Patent No. 446,861, dated February 24, 1891.

Application filed June 18, 1890. Serial No. 355,843. (No model.)

To all whom it may concern:

Be it known that I, CHARLES CARROLL GILMAN, a citizen of the United States, and a resident of Eldora, Iowa, have invented a new and useful Improvement in Underground Railway-Conduits, of which the following is a specification.

My invention relates to the construction of underground-conduits for the accommodation of wire cables used for the propulsion of cable street-railway cars.

In the accompanying drawings forming part of this specification, Figure 1 represents a perspective view of an underground cable-conduit embodying my invention, and Fig. 2 is a perspective view of a porous earthenware section, as hereinafter described.

Conduits for cable railways are generally built from three to five feet below the surface of the ground and of varying shapes, but usually cylindrical, to allow not only the free movement longitudinally of the cable therein, but the safe passage of workmen employed around and about it in oiling sheaves &c., and for the drainage of water which may pour in from the street above. It will be evident, therefore, that the properties required of the materials used in the construction of such a conduit are freedom from decay, solidity, and proof against water. Consequently the best of hydraulic cements are made to do service in this construction, the same being molded into form in large sections or blocks and cemented continuously together in the ditch in the earth. At intervals of twenty-five feet or so metal sheaves 1, grooved for the support of the wire cable 4, are suspended from the side of iron struts 2, secured to the iron yokes 3, which latter are of the form and size of a transverse section of the conduit. The yokes serve to tie the sections together to maintain their general form and prevent swerving in or out by the shifting pressure of the earth packed outside about them, and thus very properly are termed "yokes." A second and smaller yoke 5 is usually suspended within the larger, (see drawings, Fig. 1,) which serves to tie the tracks together and affords the aperture or slot for the grip to pass down or through to seize the cable. My invention has nothing to do with these devices, but only with the substitution for the

cement conduit of a conduit of like form and size, whatever that form and size may be, constructed of a different and cheaper material, 55 but every way as permanent, enduring, and water-resistant, and embodying a great improvement on other conduits of this character because of its peculiar ability to take up and absorb sound, thus silencing the din 60 caused by the rapid transit of the suspended cable or the revolving sheaves, and doing away with the roaring of passing trains caused by the reverberations from the resonant walls of the hidden conduit. This material is illustrated in Fig. 2 of the drawings, which shows a longitudinal section of porous earthenware four feet in length, three feet seven inches high, and four feet three inches extreme width, made in three longitudinal sections 6, 70 7, and 8, and united in one when placed in position, the shape as a whole being measurably the shape of the iron yokes which intersect it at intervals of twenty feet or more, 9 representing holes of arbitrary size which run 75 lengthwise through the walls of each section, being made by the manufacturers to enable the effective drying of the green compositions before firing. The iron yokes are likewise provided with similar holes to lighten their weight. 80 These compositions are manufactured under the formulas prescribed in the specification of United States Patent No. 353,631, issued to me November 30, 1886, for porous earthenware, and of course are extremely porous 85 after coming from the firing-kilns, requiring subsequent special treatment to render them water-proof—a prime necessity for the application herein described and set forth. This treatment may be of the simplest character 90 and requires no lengthy description, the material being merely dipped into boiling asphaltum or its equivalent for a sufficient length of time to enable it to penetrate below the surface to the depth of an eighth or even 95 a sixteenth of an inch, or, if preferred, may be coated with mortar or hydraulic cement troweled on or applied otherwise. If the latter material be used as the stucco, a workmanlike job requires the thorough wetting 100 of the porous slabs with water before making the application, the long subsequent dampness of the ware enabling the cement coatings to "set" into a stone-like density, never

to be detached save by disruption of the covered material itself. These sections are fitted between the iron yokes, as shown in the drawings, taking the place of the cement filling heretofore used.

I by no means limit myself to the particular size or form of the conduit described, as the material used may be applicable to any, and if not of unusual size may be turned out by a machine in one piece or more, or in the shape of blocks may be laid up as masonry. The "man-holes," "drains," and "catch-basins" usually accompanying this class of construction may also profitably be made of the same material thus treated.

Having thus described my invention, what I claim, and desire to secure by United States Letters Patent, is—

1. A railway-conduit the walls of which are constructed of porous earthenware as distinguished from ordinary earthenware, substantially as described.

2. A railway-conduit constructed of iron yokes of the form of the conduit, and of similarly-formed sections of porous earthenware as distinguished from ordinary earthenware placed in line with said yokes, substantially as described.

In testimony that I claim the foregoing as my invention I have signed my name, in presence of two witnesses, this 9th day of June, 1890.

CHARLES CARROLL GILMAN.
